TIE-DOWN HOOK FOR VEHICLES

Donald J. Blunden, Detroit, Mich., assignor to Whitehead & Kales Company, River Rouge, Mich., a corporation of Michigan

Filed June 8, 1962, Ser. No. 70,478

Term of patent 14 years

(Cl. D54—13)

FIG. 1 is a side elevational view of a tie-down hook showing my new design;

FIG. 2 is a top plan view thereof, and

FIG. 3 is a perspective view taken from the left of FIG. 2.

The broken-line showing of a section of a vehicle frame and a tensioning chain in the drawing is for illustrative purposes only.

I claim:

The ornamental design for a tie-down hook for vehicles, as shown and described.
